UNITED STATES PATENT OFFICE.

EDWARD S. STIMPSON, OF HOPEDALE, MASSACHUSETTS, ASSIGNOR TO
DRAPER COMPANY, OF SAME PLACE AND PORTLAND, MAINE.

SELF-THREADING LOOM-SHUTTLE.

SPECIFICATION forming part of Letters Patent No. 673,823, dated May 7, 1901.
Application filed June 23, 1900. Serial No. 21,266. (No model.)

To all whom it may concern:

Be it known that I, EDWARD S. STIMPSON, a citizen of the United States, residing at Hopedale, in the county of Worcester and 5 State of Massachusetts, have invented an Improvement in Self-Threading Loom-Shuttles, of which the following description, in connection with the accompanying drawings, is a specification, like characters on the drawings 10 representing like parts.

This invention has for its object the production of an improved self-threading shuttle particularly adapted for use in automatic looms—such, for instance, as shown in United 15 States Patent No. 529,940—wherein the filling-carriers are automatically inserted in the shuttle when the filling is to be replenished.

In my present invention I have simplified the construction of the threading device and 20 also that of the device for engaging and holding the head of the filling-carrier when it is inserted in the shuttle.

Various novel features of construction will be hereinafter described, and particularly 25 pointed out in the following claims.

Figure 1 is a top or plan view of a self-threading shuttle embodying my invention. Fig. 2 is an enlarged longitudinal section of the left-hand end thereof on the line $x-x$, Fig. 30 1. Fig. 3 is a similar section, also enlarged, of the right-hand end, viewing Fig. 1. Fig. 4 is a transverse sectional view of the shuttle-body on the line $x'-x'$, Fig. 2, looking to the left. Fig. 5 is an enlarged perspective 35 view of the threading end of the shuttle. Figs. 6, 7, and 8 are detail views in elevation of the threading-block, to be described; and Fig. 9 is an enlarged perspective view of the 40 device for holding the filling-carrier in position.

The shuttle-body A, having a longitudinal opening A' therein, open from top to bottom of the body to receive the filling-carrier and to permit the passage of the same there- 45 through when ejected, is of usual construc- tion, and at one end of the opening the body is recessed at a, Figs. 2 and 4, to receive the holder h, Fig. 9, made as a block having parallel upright sides and flat parallel top and 50 bottom faces. At its rear end the holder has a transverse shoulder h' formed in its top,

and a lip h² projects from said end at the bottom to enter an extension a' of the recess a in the shuttle-body, the front end of the holder having two spring jaws or arms h³, 55 which extend into the opening A'. These jaws are preferably grooved, as at 3, to receive the usual annular projections or rings on the head of the filling-carrier, which is thus engaged and held securely in position 60 in the opening A' of the shuttle.

I have shown an inclined directing-plate or guide g to assist in directing the filling-carrier into position, the guide being located between the jaws, and preferably it is made 65 of resilient metal, the lower end of the guide being bent back at g' to extend beneath the holder h, between it and the bottom a² of the recess a, and fitting into the socket a'. The upper end of the guide is bent down at g², and 70 then rearwardly extended, as at g³, upon the top of the holder, a transverse downturned lip g⁴ engaging the shoulder h' and positively locking the holder and guide together, the bend g² permitting the guide to spring or 75 yield somewhat under impact of the filling-carrier head.

Referring to Fig. 9, it will be seen that the extensions g' g³ project beyond the sides of the holder, and they enter, respectively, longitudinal grooves a⁵ a⁶, Fig. 4, near the top and at the bottom of the recess a, so that when the parts are in place they are firmly held together, the socket a' forming a continuation of the grooves a⁶. By this construction a single screw 10, passed through the holder into the walls of the shuttle-body, serves to retain the holder and guide in place, doing away with a separate screw for the latter, the spring is better adapted to stand the 90 strain of the blows, and the whole arrangement is more durable and stronger than heretofore.

At its forward end the shuttle is provided with the threading device, the wood being 95 recessed at b, Fig. 3, to receive the metal threading-block, to be described, and at the adjacent end of the opening A' the body is cut out in front of the tip of the filling-carrier, as at b', and provided with a longitudinal groove b² for the thread to travel in as it leaves the filling-carrier.

The threading-block d is a single casting having a longitudinal thread-passage d' therethrough in alignment with the groove b^2 and an overhanging laterally-extended head d^2 substantially triangular in shape. One side wall of the passage d' is longitudinally slotted at d^3 , as by a saw-cut, to form a thread-entrance to the passage, and the exterior face of the wall above it is flared or beveled, as at 8, the top edge of the wall below the slot being also beveled, but oppositely, as at 9, Fig. 7, giving a wide or flaring mouth for the thread-entrance, so that the thread can easily pass thereinto. The thread-passage and thread-entrance extend in the direction of the longitudinal axis of the shuttle, as shown. The apex of the head is downturned, as at d^4 , into a recessed portion b^3 of the shuttle-body, beyond and in front of the front end of the 20 thread-passage, and an inclined horn d^5 , best shown in Fig. 6 at the side of the passage opposite the slot d^3 , serves to guide the thread to the side delivery-eye a^{10} in the shuttle-body, the block being cutaway at the bottom 25 of horn, as at d^6 , substantially opposite the inner end of the delivery-eye. One corner of the head is bent down, as at d^7 , to register with the rear wall of the delivery-eye, (see Fig. 5,) a clearance-space b^4 for the thread to 30 travel in being formed between the top of the shuttle-body and the head intermediate the prong d^7 and downturned tip d^4 of the head.

In order to aid the thread in passing to the entrance-slot d^3 , the body of the shuttle is beveled opposite the slotted side wall of the thread-passage, as at d^8 . As the thread or yarn is drawn off the filling-carrier on the first shot of the shuttle to the left it enters 35 between the inclined walls d^5 and 8, passes under the tip d^4 , and by the beveled faces 8 40 9 is directed into the thread-entrance d^3 , and thence enters the passage d' of the threading-block. As the shuttle returns the thread 45 passes beneath the head in the clearance-space b^4 toward the prong d^7 , and the horn d^5 guides the thread to the bottom of the passage d' and into the cut-away portion d^6 , from 50 which it passes directly to the delivery-eye a^{10} , the wall a^{12} of the shuttle-body helping to 55 guide the thread fairly into the eye. The tip d^4 prevents the thread from jumping out after it enters the passage d' before it reaches the eye a^{10} . A threaded shank d^8 on the block passes through a hole in the shuttle and is held in place by a suitable nut 15, Fig. 3.

The construction described is simple and cheap, and with the threading device shown the metal is all on one side and the wood of 60 the shuttle-body on the other side of the opening which leads to the thread-entrance.

Having described my invention, what I claim as new, and desire to secure by Letters Patent, is—

65 1. A longitudinally-open shuttle-body, a holder mounted in the body at one end thereof and having jaws to engage the head of a fill-

ing-carrier, an inclined guide between the jaws, a positive detachable connection between it and the holder, and a retaining device to secure the latter in the shuttle-body, the guide being held in place solely by its positive connection with the holder. 70

2. A loom-shuttle having an opening there-in from top to bottom, a holder mounted in the body at one end of the opening and provided with jaws to engage the head of a filling-carrier, an inclined resilient guide between the jaws, said guide having a rearward extension interlocked with the holder, and a retaining device to maintain the latter in the shuttle-body. 75

3. A shuttle-body having a longitudinal opening for the reception and passage therethrough of a filling-carrier, a holder having 85 jaws to receive the head of the filling-carrier, an inclined guide extended between the jaws and having a downturned lip to engage the end of the holder, and means to secure the holder, and thereby the guide, in the shuttle- 90 body.

4. A loom-shuttle having a longitudinal opening for the reception of the filling-carrier, a longitudinally-grooved recess in the shuttle-body at one end of the opening, a 95 holder inserted in said recess and having jaws to engage the head of a filling-carrier, an inclined guide between the jaws having a rearward extension projecting into the said grooves and interlocked with the holder, and 100 a retaining device to secure the holder in place.

5. A shuttle-body having a recess in one end thereof provided with longitudinal grooves, a holder inserted in the recess and having 105 spring-jaws to engage the head of a filling-carrier, and a resilient inclined guide between the jaws, the ends of the guide being extended rearwardly to embrace the holder and to enter the grooves in the shuttle-body. 110

6. A holder having a pair of spring-jaws to engage the end of a filling-carrier, said holder having on its top a transverse shoulder at its end opposite the jaws, and a co-operating guide inclined between the jaws and having its ends 115 bent back to receive between them the holder, one end having a lip to engage the shoulder on the holder.

7. In an automatically-self-threading shuttle, a block provided with a thread-passage 120 having a thread-entrance in one of its longitudinal side walls, said passage and entrance being extended longitudinally of the shuttle, the outer face of the said side wall being beveled outwardly from the said entrance to the 125 top of the block.

8. In an automatically-self-threading shuttle, a block provided with a thread-passage having a thread-entrance in one of its longitudinal side walls, said passage and entrance 130 being extended longitudinally of the shuttle, the overhanging portion of said wall being externally beveled and the top of the lower portion of the wall being oppositely beveled.

9. In an automatically-self-threading shuttle, a block having a thread-passage therethrough, having a side slot forming the thread-entrance, said passage and entrance being extended longitudinally of the shuttle, the edges of the slot being externally flared, and a horn the head of which extends beyond the front end of the thread-passage, the head being provided with a thread-detent.
10. In an automatically-self-threading shuttle having a side delivery-eye, a block having a longitudinal thread-passage therethrough substantially in the longitudinal axis of the shuttle, a horn having a substantially triangular head the apex of which is downturned
- 5
- 15
- beyond the front of the thread-passage, a depending prong on the head, to assist in guiding the thread into the delivery-eye, and a longitudinal side entrance for the thread-passage, the shuttle-body being recessed adjacent thereto and beveled, to direct the thread into the entrance. 20
- In testimony whereof I have signed my name to this specification in the presence of two subscribing witnesses.

EDWARD S. STIMPSON.
